UNITED STATES PATENT OFFICE.

CÉCILE MOREAUX, OF NEW YORK, N. Y.

DEVICE FOR CARRYING ARTICLES FROM THE WRIST.

Application filed December 5, 1923. Serial No. 678,633.

To all whom it may concern:

Be it known that I, CÉCILE MOREAUX, a citizen of the United States, residing at New York, in the county of New York and 5 State of New York, have invented certain new and useful Improvements in Devices for Carrying Articles from the Wrist, of which the following is a specification.

This invention is a novel device for carrying articles from the wrist, and is useful, for example, for carrying ladies' pocket books or shopping bags. The main object is to produce a superior article of this kind. Other objects are to give safety without introducing features of inconvenience; to enable the article to be rendered ornamental where it over lies the wrist so as to produce the effect of a bracelet; to permit ease of application and removal; and to give 10 ready adjustment. To the attainment of these objects and advantages the present invention consists in the novel device, and the novel features of combination, arrangement and detail, as herein shown or described.

25 In the accompanying drawings Fig. 1 is a perspective view showing the device in use, in this case being used for suspending a bag from the wrist.

Fig. 2 is a face view of the short flexible 30 member or element detached.

Fig. 3 shows a portion of the same, pulled into stretched condition, to show its stretchability, and the means of limiting the stretch.

35 The particular illustrated embodiment may be briefly described as follows. The bag 4 may have the usual clasp 5 and a suspending strap, cord or chain 6. This member 6 is a continuous flexible member from the ends of which the article or bag 40 is suspended. In the use of this invention it is preferred that no part of the suspending flexible member 6 shall overlie the wrist, but a portion 7 thereof extends underneath the wrist.

45 The suspending flexible member 6 is formed with a number of attaching points or apertures 8, and in the case of the use of a chain the links of the chain readily provide such apertures.

50 The other member or element 9 of the present invention consists of a short flexible member connected at two points to the suspending member so that the wrist may be inserted and thus surrounded by the two members, giving safety and the other ad-

vantages mentioned. Preferably the short member overlies the wrist with its ends engaged with separated points on the suspending member, the latter underlying the 60 wrist.

The short flexible member 9 is preferably a separate, detachable or independent member having means at its ends for detachable connections to the suspending member 6. Such fastening means may consist of snap hooks 10 at the two ends of the short member 9, and these hooks are adapted to snap into the apertures or links of the suspending member 6. 65

70 By this arrangement the body 11 of the short flexible member may be of a nature to rest comfortably upon the wrist, and of suitably ornamental nature, for example, by being constructed of a precious metal and 75 in attractive design. The illustrated body 11 of the member 9 may be considered as constructed of gold plated spring wire, this giving the effect of a bracelet. In a sense 80 the member 9 is a half bracelet or part bracelet, which does not reach entirely around the wrist, but is provided with fasteners at its ends for detachable connection to the suspending member of the bag.

85 A convenient construction for the short member is of spring wire as stated, this giving it the ability to stretch, rendering it expandable for convenient insertion of the hand. The expansion or stretch of the body 11 of the member 9 however is preferably 90 limited and for this purpose non-stretchable cords or wires 13 may be applied inside of the coiled wire 12, and secured at the ends to the snap hook mounting.

95 It will thus be seen that I have described a device of the character mentioned, securing the advantages of the present invention. Since various matters of design, arrangement and detail may be modified without departing from the underlying features of 100 invention it is not intended to limit the invention to such matters except so far as specified in the appended claims.

What is claimed is:

1. In a device to carry a bag or other 105 article from the wrist, the combination of a continuous flexible suspending member looped above the article to be carried, and a short stretchable bridging member extending across between two separated points on the suspending member and connected at its ends to such points, whereby the wrist may 110

be inserted and is surrounded by the bridging and part of the suspending member.

2. A device as in claim 1 and wherein the bridging member comprises a metallic spring formed in convolutions and adapted to overlie the wrist.

3. A device as in claim 1 and wherein the bridging member is freely stretchable to a predetermined point and is provided with

means to prevent stretch beyond such point. 10

4. A device as in claim 1 and wherein the suspending member is formed of connected links, and the bridging member is connected to two such links at separated points. 15

In testimony whereof, I have affixed my signature hereto.

CÉCILE MOREAUX.
